UNITED STATES PATENT OFFICE.

SYLVESTER L. JOINER, OF McGREGOR, TEXAS.

REVERSIBLE PLACARD HOLDER FOR TANK CARS.

Application filed March 30, 1926. Serial No. 98,535.

The invention relates to a reversible placard holder for tank cars.

The object of the present invention is to improve the construction of reversible placard holders for tank cars and to provide a simple, practical and efficient reversible placard holder of strong, durable and comparatively inexpensive construction adapted to meet railroad requirements and capable of being readily reversed for indicating when a tank car is empty or full without necessitating the person changing the position of the reversible placard, climbing upon the running board upon which placard holders are usually mounted.

Commonly such placards consist of printed sheets secured to uprights mounted on the running board or other portion of the car frame or running gear, and located at the ends of the car at both sides thereof, one of the placards being used for indicating that the tank car is full and another for designating when the tank car is empty.

Another object of the invention is to provide a reversible placard holder in which the placard will be rigidly held in position and in which there will be no liability of the vibration of the device incident to train motion either changing the position of the placard or loosening the reversible construction.

With these and other objects in view, the invention consists in the construction and novel combination and arrangement of parts hereinafter fully described, illustrated in the accompanying drawings and pointed out in the claims hereto appended, it being understood that various changes in the form, proportion and minor details of construction, within the scope of the claims, may be resorted to without departing from the spirit or sacrificing any of the advantages of the invention.

In the drawings:—

45 Figure 1 is an elevation partly in section of a reversible placard holder for tank cars constructed in accordance with this invention.

Fig. 2 is a vertical sectional view of the
50 same, the placard being reversed.

Fig. 3 is a vertical sectional view through the socket and shank taken at right angles to Fig. 2.

Fig. 4 is a horizontal sectional view on the line 4—4 of Fig. 2.

Fig. 5, is a detail, sectional view, taken transversely, of the housing of the latch.

Fig. 6 is a detail view of the latch bolt.
Fig. 7 is a side elevation of my invention showing the same attached to the running board of a tank car.

In the accompanying drawing in which is illustrated the preferred embodiment of the invention 1, designates a reversible placard designed for use on tank cars and constructed of suitable metal to render it practically indestructible and having the lettering applied to it in any suitable manner. Placards are required to be placed on tank cars containing inflammable liquids notifying railroads and other companies of the class 65 70

road companies and others of the inflammable and dangerous nature of the contents of the tank or the interior of the tank after the contents have been removed and until all the inflammable vapors have been displaced and it is the usual practice to use one placard which is applied to the car when the tank is full and another placard

which is applied to the car after the contents have been removed from the tank. 80
The indestructible reversible placard will be provided on its faces with the matter corresponding to the two placards usually employed on tank cars and meeting the legal requirements of the same. 85
The reversible metallic placard, which is

rectangular is mounted in a slot or bifurcation 2 of a shank 3 with its diagonals arranged vertically and horizontally as shown in the drawings and it is riveted or otherwise secured in the slot or bifurcation of the shank which is reduced intermediate of its ends to provide a shoulder 4 and a lower squared portion 5 which fits in a rectangular opening 6 of a vertical socket 7. The shoulder is adapted to rest upon the upper edges of the socket 7 which constitutes an upright portion of an L-shaped bracket 8 having a horizontal attaching portion 9 of a length to extend entirely across the lower face of the running board 10 of a tank car and bolted or otherwise secured to the same. The bracket is designed to consist of a single piece or casting of malleable iron or other suitable metal and the polygonal character of the opening of the socket and the shank will prevent any rotary movement of the shank and the placard in the socket of the bracket so that it is necessary to remove the shank from the socket and reverse the former and the

placard carried thereby before replacing the shank in the socket. This may be done by a railroad employee or other person without climbing upon the running board of the 5 car.

The shank is secured in the socket by means of a horizontal spring actuated pin or bolt 11 mounted in a tubular casing or housing 12 and provided at its outer end with a 10 head 13 forming a suitable grip or handle for enabling the spring actuating pin or bolt to be readily manipulated. The pin or bolt extends through registering openings 14 and 15 in the shank and the socket and 15 it has disposed on it a coiled spring 16 which is interposed between a car 17 of the pin or bolt and a flange 18 or suitably formed of scallops provided at the outer end of the casing or housing. The bolt is provided with 20 a longitudinal flange 19 slotted at the inner portion at 20 for the coiled spring 16 and being of a length substantially the same as the thickness of the shank and one of the side walls of the socket and operating in a groove 25 21 in the casing or housing. The bolt or pin is adapted to be withdrawn a sufficient distance to enable the flange to clear the outer end of the housing and the bolt or pin which is round may be then rotated to 30 carry the flange away from the groove 21 whereby the flange is adapted to hold the pin or bolt in a retracted position and out of engagement with the shank of the reversible placard to enable the latter 35 and the shank to be removed from the socket and reversed. After the placard has been thus adjusted the bolt or pin is partially rotated to return the flange to the groove in the casing or housing and permit the spring 40 to actuate the said pin or bolt and carry the same into engagement with the shank of the reversible placard. By this construction the shank will be firmly secured in the socket

of the bracket and there will be no liability of jar or vibration changing the position of 45 the placard. The casing or housing 12 is preferably threaded at the inner end at 22 and secured in a threaded opening in the adjacent wall of the socket.

In order to prevent the reversible placard 50 from becoming lost or misplaced a chain 23 is employed for connecting the shank with the socket. The chain which is secured at one end to the socket and at the other end to the shank is of sufficient length to enable 55 the reversible placard to be conveniently handled.

What is claimed is:

A reversible placard holder for tank cars comprising a bracket including a lower attaching portion and a substantially vertical one piece socket member provided with side and bottom walls rising from the attaching portion and having an opening polygonal in cross section, a reversible placard having opposite placard faces and provided with a shank having an upper portion to support a placard, the shank having a lower portion which is polygonal in cross section provided with a shoulder intervening between the upper tapering and the lower polygonal portions of the shank, the lower polygonal portion of the shank fitting in the socket of the bracket with said shoulder of the shank resting on the top of the socket and the end 75 of the shank engaging the bottom of the socket, the cross sectional shape of the lower portion of the shank in the socket interlocking the shank against rotary movement in the socket, the shank being removable from 80 the socket to reverse the placard, and means carried by the socket for locking the shank against removal from the socket.

In testimony whereof I have hereunto set my hand.

SYLVESTER L. JOINER.
